UNITED STATES PATENT OFFICE.

FERDINAND C. GAMMONS, OF BRIDGEWATER, MASSACHUSETTS, ASSIGNOR
TO THE EAGLE COTTON GIN COMPANY, OF SAME PLACE.

RIB FOR COTTON-GINS.

SPECIFICATION forming part of Letters Patent No. 332,069, dated December 8, 1885.

Application filed September 21, 1885. Serial No. 177,738. (No model.)

To all whom it may concern:

Be it known that I, FERDINAND C. GAMMONS, a citizen of the United States, residing at Bridgewater, in the county of Plymouth and State of Massachusetts, have invented 5 certain new and useful Improvements in Ribs for Cotton-Gins, of which the following is a full, clear, and exact specification.

My invention relates to the ribs which form 10 the breast of the "Eclipse Hulling-Gin," an illustration of which may be seen in Letters Patent No. 20,120, granted on the 27th of April, 1858, to Wilson and Payne. Usually each rib is provided with a flange, which projects therefrom midway between its edges, so as to be equidistant from the two adjacent saws on its opposite sides. The objection to this form of 15 rib is, that the descent of cleaned seed from the hulling-chamber is obstructed by the seed-cotton, which is constantly being carried from the hulling to the ginning chamber by the saws. To overcome this objection it has been proposed to join the flange to the edge instead of the center of the rib, so that the space between 20 each two adjacent saws, which is usually divided equally upon opposite sides of the flange, is merged into one. While this facilitates the descent of the cleaned cotton-seed, it is objectionable, for the reason that by 25 joining the flange to the edge of the rib it is brought into such close proximity to the saw as to materially interfere with the upward passage of the seed-cotton.

The object of my present invention is there- 30 fore to provide a rib which shall be free from

both of these objections, permitting the free upward passage of the seed-cotton and the free downward passage of the cleaned cotton-seed.

To this end my invention consists of a rib having a flange joined thereto between the center and the edge thereof, as will be more fully described with reference to the accompanying drawings, in which—

Figure I is an elevation of the convex side of a rib of the improved form. Fig. II is a 4 transverse section thereof on the line II II, Fig. I.

a represents the rib, and *b* is the flange which joins it, as represented, between the center and the edge, the space between the 5 base of the flange and the edge of the rib being about one-eighth of an inch. This may, however, be slightly varied without departing from my invention.

c represents the lateral enlargement at the 10 lower or front extremity of the flange *b*, for freeing the seed-cotton of any foreign substance—such as seed-pods—that may cling to it.

Having thus described my invention, the 15 following is what I claim as new therein and desire to secure by Letters Patent:

A rib for cotton-gins, having a flange joined thereto between the center and edge thereof, substantially as and for the purpose set forth. 20

FERDINAND C. GAMMONS.
